UNITED STATES PATENT OFFICE.

SOMA HERZOG, OF NEW YORK, N. Y., ASSIGNOR TO UNIVERSAL BOTTLE CLOSURE CO., INC., OF NEW YORK, N. Y., A CORPORATION OF NEW YORK.

BOTTLE-CLOSURE.

1,279,343.

Specification of Letters Patent. Patented Sept. 17, 1918.

Application filed September 30, 1916. Serial No. 123,167.

To all whom it may concern:

Be it known that I, SOMA HERZOG, a citizen of the United States, residing at New York, in the county of New York and State 5 of New York, have invented certain new and useful Improvements in Bottle-Closures; and I do hereby declare the following to be a full, clear, and exact description of the invention, such as will enable others skilled in 10 the art to which it appertains to make and use the same.

This invention relates to bottle closures and more particularly to that type wherein a valve member is interposed in the mouth 15 of a bottle or container and in which provision is made for actuating said valve member.

An object of this invention is to provide a closure for bottles or other containers, in 20 which the discharge of liquids from the container may be controlled and regulated irrespective of the nature of the liquid being dispensed.

A further object of this invention is the 25 provision of a valve member inserted in the neck of a bottle or container, a retaining member for supporting said valve and an actuating member carried by said valve being detachably carried thereby.

30 A further object of this invention is the provision of a bottle closure comprising a valve member insertible in the neck of a bottle, a retaining member for supporting said valve member, said valve member and 35 retaining member having threaded connection with each other and said retaining member being locked to the bottle to avoid accidental displacement in the operation of the valve member.

40 Further objects will be apparent from the following specification, appended claims and drawings, in which,

Figure 1 is a vertical sectional view of parts of a vacuum bottle showing this invention applied thereto,

Fig. 2 is a horizontal sectional view as on the line 2—2 of Fig. 1,

Fig. 3 is a similar view as on the line 3—3 of Fig. 1,

Fig. 4 is a side elevation of a retaining member,

Fig. 5 is a side elevation of the valve member removed,

Fig. 6 is a vertical sectional view of an 55 other form of supporting means,

Fig. 7 is a horizontal sectional view as on the line 7—7 of Fig. 6,

Fig. 8 is a similar view as on the line 8—8 of Fig. 6, and

Fig. 9 is a perspective view of a slightly 60 modified form of valve member.

This invention provides for the formation of a bottle closure in which a valve seat is 65 formed in the neck of the bottle or other container, and a valve is movably carried 70 in the neck of said container to permit its being seated to close the passage through the neck of the bottle or said valve may be unseated upon actuation of manipulating means carried by said valve exteriorly of 75 said bottle.

Referring to the drawings, in which the several parts are clearly shown, 10 indicates the casing of a vacuum bottle having the removable intermediate section 11 to permit 75 insertion of the doubled wall container 12 within the casing 10 and this intermediate section is threaded as at 13 to receive the cap member 14. The sleeve 15, having the threaded enlargement 17 formed thereon, is 80 insertible in the threaded section 13, where the gasket 18 or other sealing means, may be interposed between the upper extremity of the section 11 and this sleeve. The sleeve 15 has an inwardly directed flange 19 formed 85 therein and the sleeve is recessed as at 20 to receive the packing 21 which lies under the flange 19, so that when the section 11 is attached within the shell 10, the packing 21 forms a seal against the upper edge of the 90 container 12. The upper face of the flange 19 forms a valve seat against which a washer 22 carried by the valve member 23 presses in seated position, to effectively seal the passage through the neck of the bottle. 95 The upper edge of the sleeve 15 is internally threaded as at 24 to receive the retaining ring or cap 25 on which the overhanging flange 26 is formed to compress the washer 27 between the flange 26 and upper edge 100 of the sleeve 15, to thereby seal the passage between these members.

The valve 23 comprises the diaphragm which normally overlies the opening in the neck of the bottle and this valve has the 105 depending guide 28 formed thereon, in which the passages 29 are formed and above this diaphragm is a wall 30, in which the openings 31 are formed which communicate with an interior chamber 32 and this chamber has 110

communication with the exterior of the bottle as through a passage 33. The passage 33 is formed through a stem 34 on which the threads 35 are formed and these threads are 5 of relatively large proportions, being cut to a considerable pitch, as by using double threads thereabout, so that quick action in the movement of the valve may be had upon rotation of said stem. In the formation of 10 the stem 34, a shoulder 55 is formed upon which a washer 56 is placed, so that as the stem is rotated in one direction, this washer 56 forms a seal with the lower face of the head 25 to prevent the passage of liquid 15 about the same. The threads 35 engage the interiorly threaded opening 36 in the head 25 and the threads 35 are cut in opposite direction to the external threads on the head 25, so that when the head 25 is locked in the 20 upper edge of the sleeve 16, manipulation of the valve stem 34 does not tend to loosen the locked relation of the head. The stem rising above the head 25 is reduced as at 37 and has the pins 38 formed thereon to permit 25 said valve stem being operated as by a removable actuating member 39, which has the T-slots 40 formed therein to permit the vertical portions of said slots passing over the lugs 38 when the actuating member is 30 applied, after which said actuating member may be moved in either direction as to cause the lugs 38 to enter either of the branches of said slots when it is desired to move the valve stem in either direction, as to open 35 or close the passage. The diaphragm 23 will be of less diameter than the internal diameter of the sleeve 15 above the flange 19, but as it is desired to form the guides for said valve, lugs 41 are formed on the 40 edges of said diaphragm and it is evident that these lugs contact with the interior wall of the sleeve, when said valve member is eccentrically disposed therein, to assure the proper vertical movement of said valve.

45 Fig. 6 is a slight departure from that above described in having the closure applied to a bottle of ordinary formation in which the bottle is indicated as at 42 having a ring 43 frictionally held therein to serve 50 in the formation of a restricted passage and in affording a valve seat. 44 indicates the valve having the depending guide 45 formed thereon, in which the passages 46 are cut and this valve is carried by a pin 47 which 55 depends from a cage construction 48 carried centrally within the cap member 49 which has its overhanging edges threaded as at 50 to operate on the thread 51 formed on the exterior wall of the bottle neck. In 60 this form, the screw threaded connection between the cap and bottle forms the actuating

means for the valve member as it is clearly seen that the valve may be seated to close the passage upon manipulation of the cap in one direction, or the valve may be unseated to permit discharge of the contents of the bottle upon reverse movement of the cap. 65

Fig. 9 shows a valve member of slightly modified construction in which 52 indicates 70 the diaphragm having the lugs 53 formed thereon, and depending from this diaphragm is the guide comprising the wings 54 which may be radially disposed about a common center. 75

As shown in Fig. 1, the sleeve 15 may be made of metal or of vitreous material when used in connection with vacuum bottles and it is evident in view of the foregoing, that numerous other modifications may be made 80 without departing from the spirit of this invention, as the drawings are submitted for illustrative purposes only. It is also thought that the operation of the several parts is clear in view of the foregoing and 85 that further description is unnecessary.

Having thus described my invention, I claim:

A bottle closure of the class described comprising in combination, a container having a 90 valve chamber formed in the neck thereof, an inwardly directed flange forming a valve seat and a central opening in the container neck, a cap removably carried by said container having threaded engagement with the 95 side wall of said valve chamber, a valve movably mounted in said valve chamber, said valve comprising a diaphragm to overlie the central neck opening, a guide depending from said diaphragm, a valve stem rising 100 above said diaphragm having a central passage therein and communicating passages between the central passage and the interior of said valve chamber, said valve stem having a reduced and externally threaded portion, 105 having the threads cut at an abrupt pitch and in the reverse direction to those on the cap, said cap having a threaded passage to receive said threaded valve stem, said valve stem being further reduced above said cap 110 and having lugs diametrically formed thereon, an operating nut having T slots formed therein to receive said lugs on said valve stem, having a limited free movement on said valve stem for rotating said valve stem 115 to seat or unseat said valve, and washers carried by said valve to seat on said inwardly directed flange and against said cap in the limits of movement of said valve in either direction. 120

In testimony whereof I affix my signature.
SOMA HERZOG.
